MOLD PRESS FOR CIGAR MACHINES

Filed Dec. 22, 1933

FIG. 1

UNITED STATES PATENT OFFICE

1,977,976

MOLD PRESS FOR CIGAR MACHINES

Verner J. Wahlstrom, Brooklyn, N. Y., assignor
to International Cigar Machinery Company, a
corporation of New Jersey

Application December 22, 1933, Serial No. 703,629

6 Claims. (Cl. 131—9)

This invention relates to mold presses for cigar bunch machines, its main object being to close the bunch molds automatically by the action of the machine itself.

5 In making scrap bunches, it is the practice to place the rolled bunches one by one into the cigar-shaped pockets of a mold. These molds, when filled, are closed by the operator with a cover which has shaped projections registering with 10 the aforesaid pockets of the mold and together with the latter defining the desired shape of the bunch. To complete the bunch-shaping operation, the operator heretofore had to force the mold cover down into its proper place in the 15 grooves by manipulating a hand press installed in some convenient place near the bunch machine.

To eliminate the loss of time caused by this manipulation and at the same time to do a much 20 better job, the mold press in the present invention is incorporated with the bunch machine in such a manner that the drive of the latter drives home the cover. A suitable mold-compressing mechanism, such as a toggle, is actuated by a 25 cam once in every cycle of the machine, thereby imparting a closing motion to the mold cover every time a new bunch is being rolled, thus exerting a tamping action on the bunches in the closed mold for every bunch placed in the open 30 mold, the total number of successive mold closings corresponding to the number of grooves in the molds, usually about 20. When the open mold is filled, the closed mold is removed from the press and the newly filled mold inserted in 35 its place. The mold-compressing mechanism is so synchronized with the bunch-rolling mechanism that the mold-press is open at the time a rolled bunch has been ejected from the rolling apron and while the machine is at rest, thus enabling the operator to remove the old mold from 40 the press and to insert a new mold not only after the new mold has been completely filled, but even upon the discharge of any individual bunch, as may be required at the end of a run, with the 45 last mold only partly filled.

Another object of the invention is the provision of a toggle-operated mold press. With these and other objects in view, the invention consists in certain constructions and combinations hereinafter described and then specifically set forth in the appended claims.

50 In the accompanying drawing which forms a part of this specification and in which like characters of reference indicate the same or like parts:

Fig. 1 is a side elevation of the automatic mold-press shown incorporated with a cigar bunch machine and operated from the cam shaft of the latter;

60

Fig. 2 is a front elevation of Fig. 1;

65

Fig. 3 is a top view of Fig. 1; and

Fig. 4 is a diagrammatic view showing the time-relation of the mold-compressing mechanism with the bunch rolling mechanism of the cigar machine.

65

In carrying the invention into effect there is provided a stationary base adapted to support a cigar bunch mold having a plurality of bunch shaping pockets and a removable cover, and toggle-operated means for intermittently pressing 70 said cover down on the mold to drive it home and shape the bunches in said pockets. In the best constructions contemplated said means includes a pair of vertical posts slidably mounted in said base on either side of the mold, a press-head pivotally mounted in the upper ends of the posts, and a cam-actuated toggle connected to the posts. These various means and parts may be widely varied in construction within the scope of the 75 claims for the particular device selected to illustrate the invention is but one of many possible concrete embodiments of the same. The invention, therefore, is not to be restricted to the specific construction shown and described.

80

Referring to Figs. 1 to 3, the bed plate 5 of the 85 cigar bunch machine which is supported by side frames 6 carries the base 7 of the mold press. The base 7 is provided with vertical bearings 8 in which are carried slides posts 9 supporting a horizontal shaft 10 on which is mounted 90 the press-head 11. The latter has sockets 11a engaging the posts 9, the bore of these sockets being somewhat larger than the diameter of the posts to permit the head 11 to tilt slightly and thereby adjust itself to any inclination of the 95 cover which may occur while it is being forced down on the mold. The head 11 carries press plates 12, floatingly mounted on the same by means of pins 13 held in the shanks of plates 12 by set screws 14 and fitted into transversal bores 100 in the press-head having a greater diameter than the pin diameters. The floating mounting of the press plates permits them to engage the mold cover squarely in any tilted position of the press head.

105

In the base 7 between the bearings 8 is fixed a stud 15 on which is pivoted one member 16 of a pair of toggle levers, the other member 17 being pivoted on a stud 18 connecting the bottom ends of posts 9. The toggle stud 19 joining 110

the members 16 and 17 is connected by a link 20 to a cam lever 21 fulcrumed on a stud 22 carried by a bracket 23 attached to base 7. The cam lever 21 has a roller 24 held in engagement 5 with a cam 25 on the cam shaft 26 of the cigar bunch machine by a spring 27 anchored to a post 28 in side frame 6. The posts 9 are partly cut away for a sufficient distance above the bearings 8 to reduce the width of the press for a given 10 maximum size of mold. The base 7 has a rearward extension 29 supporting a screw 30 which acts as a stop when inserting the mold M. In the extension 29 are slidable side guides 31 which are held in place by set screws 32 and serve to 15 center the mold M on the base 7. Brackets 33 and 34 attached to side frame 6 carry adjustable screws 35 which engage with lugs 36 of base 7 and serve as additional supports for the base 7.

Referring now to Fig. 4, the cam shaft 26 of 20 the cigar bunch machine on which the press-actuating cam 25 is mounted, has a cam 37 engaging with a cam lever 38 operating, through a link 39, an arm 40 carrying the bunch rolling pin 41. The cams 25 and 37 are so related on 25 shaft 26, that the posts 9 are raised with the press-head 11 and the press-plates 12, thus opening the press, by means of cam lever 21, link 20 and toggle lever 17 and 16, whenever the lever 38 is moved into the position shown. In this 30 position of lever 38 arm 40 causes the rolling apron 42, which passes over rolling pin 41, to discharge a rolled bunch B into a clamp 42 provided at the end of the rolling table to receive the same. Since the bunch machine automatically stops at the end of every bunch rolling cycle, the improved mold press therefore is always 35 ready for the removal or insertion of a mold during these rest periods.

What is claimed is:

- 40 1. In an automatic mold press, the combination with a stationary base adapted to support a cigar bunch mold having a plurality of bunch shaping pockets and a removable cover, of toggle-operated means for intermittently pressing said cover down against the mold to drive the cover home and shape the bunches in said pockets.
- 45 2. In an automatic mold press, the combination with a stationary base adapted to support a cigar bunch mold having a plurality of bunch shaping pockets and a removable cover, of toggle-operated means for intermittently pressing said

cover down against the mold to drive the cover home and shape the bunches in said pockets, said means including a pair of vertical posts slidably mounted in said base on either side of the mold, a press-head pivotally mounted in the upper ends of said posts, and a cam-actuated toggle connected to said posts. 80

3. In an automatic mold press, the combination with a stationary base adapted to support a cigar bunch mold having a plurality of bunch shaping pockets and a removable cover, of toggle-operated means for intermittently pressing said cover down against the mold to drive the cover home and shape the bunches in said pockets, said means including a pair of vertical posts slidably mounted in said base on either side of the mold, a press-head pivotally mounted in the upper ends of said posts, 85 press plates floatingly mounted in the ends of said head, and a cam-actuated toggle connected to said posts. 90

4. The combination with a cam-shaft of a cigar bunch rolling mechanism, of an intermittently operating cigar bunch mold-press driven from said shaft and synchronized with said mechanism so that the mold-press is open at the time 100 the rolled bunch is ejected by said mechanism and while the latter is at rest, whereby the attendant of the bunch rolling mechanism may remove the mold from said press and replace it by a newly filled mold, while the press is open, not 105 only after the latter has been completely filled by the attendant with bunches ejected from said mechanism, but even upon the discharge of any individual bunch, as may be required at the end of a run, with the last mold partly filled. 110

5. Means for intermittently pressing a mold cover down against a cigar bunch mold, comprising a pair of vertically reciprocable posts disposed to receive the mold therebetween, a press-head pivotally mounted in the upper ends of said posts, 115 and a cam-actuated toggle connected to said posts.

6. Means for intermittently pressing a mold cover down against a cigar bunch mold, comprising a pair of vertically reciprocable posts disposed to receive the mold therebetween, a press-head pivotally mounted in the upper ends of said posts, 120 press plates floatingly mounted in the ends of said head, and a cam-actuated toggle connected to said posts. 125
